UNITED STATES PATENT OFFICE.

GARTH G. GILPIN, OF RIVERSIDE, ILLINOIS, ASSIGNOR TO P. H. MURPHY COMPANY, OF NEW KENSINGTON, PENNSYLVANIA, A CORPORATION OF PENNSYLVANIA.

CAR ROOF.

Application filed February 28, 1921. Serial No. 448,290.

To all whom it may concern:

Be it known that I, GARTH G. GILPIN, a citizen of the United States, residing at Riverside, in the county of Cook and State 5 of Illinois, have invented new and useful Improvements in Car Roofs, of which the following is a specification.

This invention relates to improvements in car roofs for freight cars and more particularly to the type known as all metal roofs in which the roof sheets extend from side to side with their eaves ends rigidly secured to the side plates of the car frame.

It is an object of this invention to so construct the meeting edges of the roof sheets that they will form in effect a carline so that the roof will be self sustaining, and another object of this invention is the arrangement of the meeting edges of the roof sheets in such a manner that they may be riveted together and the rivet holes be so placed that they will not form a ready ingress for water should the rivets become loose. Another object of this invention is to so strengthen the roof sheets at their meeting edges as to allow of the use of light weight material and at the same time simplify the bending or pressing operation in forming the strengthening members.

While the preferred forms of this invention are illustrated upon the accompanying sheets of drawings yet it is to be understood that minor detail changes may be made without departing from the scope thereof.

Fig. 1 is a plan view of a portion of a car roof embodying this invention, with parts broken away.

Fig. 2 is a view in vertical section taken on the line 2—2 of Fig. 1 looking in the direction of the arrows.

Fig. 3 is a view in side elevation of Fig. 1, with parts broken away.

Fig. 4 is a view in section taken on the line 4—4 of Fig. 2.

Fig. 5 is a view in section taken on the line 5—5 of Fig. 2.

Fig. 6 is a view in section taken on the line 6—6 of Fig. 2.

Fig. 7 is a view in section taken on the line 7—7 of Fig. 2.

In the embodiment of the invention as shown upon the accompanying drawings each roof sheet 1 extends from side to side of the car with the eaves ends bent down

over the side plates 2 and preferably rigidly secured thereto by rivets 3.

One edge of each roof sheet is provided with an upstanding flange 4 which extends continuously from end to end, and the other edge is provided with a struck up rib 5 formed by bending or pressing the edge at right angles to the body of the sheet, forming the top of the rib at right angles thereto, and forming the other side spaced apart downwardly and parallel to the first side, as shown in Fig. 4. When in position on the car frame the free spaced apart edge of the rib of one sheet overlaps the upstanding flange of the adjacent sheet, as shown in Fig. 4. The height of the rib 70 above the body of the roof sheets remains constant for an equal distance on each side of the longitudinal center line and then gradually decreases until adjacent the side plates when it more rapidly decreases until 75 the rib portion of one sheet lies over the body of the adjacent sheet. The sheet originally being of rectangular form and the first bending of the rib portion and the upstanding flange of the opposite edge being 80 in planes at right angle to the longitudinal center of the car, the excess metal formed caused by the reduction in the height of the rib is utilized to strengthen the construction 85 by flanging the free edge of the rib portion outwardly to rest upon the body of the adjacent sheet and the upstanding flange overlapped thereby is bent outwardly at its upper edge so that it will remain in contact 90 with the side and top portion of the rib, and as it approaches the eaves ends will 95 merge into the plane of the body of its sheet, as shown in Figs. 6 and 7.

The meeting edges of the sheets are provided with a plurality of corresponding rivet holes and as these edges are in a vertical plane when the sheets are secured by the rivets 3^a, water or rain will not readily seep therethrough should the rivet holes become enlarged or the rivets loose.

The running board 6 is preferably supported upon an angle 7 to which it is bolted or otherwise secured and which in turn is attached to the free side of the rib 5 by rivets 8 which also pass through the angle and edge of the rib in a horizontal plane.

In this construction the plates from which the roof sheets are made are of uniform size,

the bending or pressing operation is simple and is accomplished without any waste of material or shearing of excess metal. Each sheet is of similar construction, the rib of one overlapping the upstanding flange on the edge of the adjacent sheet. The struck up ribs and flanges add sufficient strength to the sheets to obviate the necessity of car lines. The more rapidly decreasing height of the rib as it approaches the eaves end of the sheet and the straightening out of the upstanding flange of the adjacent sheet at this point interlocks the sheets together without the necessity of rivets and the constantly increasing flange 9 of the rib edge as it approaches and lays over the eaves end of the adjacent sheet provides a means of additional strength to the rib and a means for securing the overlaying end portion to the side sill.

What I claim is:

1. A car roof comprising metal roof sheets extending from eaves to eaves having their ends secured to the car frame, each sheet having one margin provided with a struck up rib having spaced apart parallel side walls decreasing in height from ridge to eaves, the outer side wall terminating short of the body of the contiguous sheet at the ridge and flanged out to lay thereover as the height of the rib decreases, with the opposite margin provided with an upstanding flange

adapted to be received within the rib of the contiguous sheet and secured upon the interior of the outer wall thereof, said flange being bent over at the top as the rib decreases in height to contact with the top of said rib, the upstanding portion decreasing in height towards the eaves with the bent over portion increasing in width until the both portions flatten out and merge into the plane of the body at the eaves with the increasing flange of the outer rib wall of the contiguous sheet laying thereover.

2. A metallic roof sheet of rectangular shape for freight cars adapted to extend from side to side of the car, the margins of one side struck up to form a rib having spaced apart parallel side walls decreasing in height from ridge to eaves, the outer side wall terminated short of the plane of the body of the sheet at the ridge with the excess metal flanged outward in a plane lying over the body of the sheet as the height decreases, and the margin of the opposite side having an upstanding flange parallel to and of less height than the said rib which as the rib decreases in height decreases proportionately with the excess metal bent out in a plane lying on the under side of the top of the rib until both portions of the flange merge into the plane of the body of the sheet at the ends.

GARTH G. GILPIN.
